UNITED STATES PATENT OFFICE.

GENERAL E. BUTTON, OF NAMPA, IDAHO.

ADVERTISING CHAIR.

Application filed February 15, 1921. Serial No. 445,158.

To all whom it may concern:

Be it known that I, GENERAL E. BUTTON, a citizen of the United States, residing at Nampa, in the county of Canyon and State 5 of Idaho, have invented certain new and useful Improvements in Advertising Chairs, of which the following is a specification, reference being had therein to the accompanying drawing.

10 My invention relates to improvements in advertising chairs.

An important object of the invention is to provide an advertising chair, formed of few and simple parts.

15 A further object of the invention is to provide means whereby the display element or belt may be readily removed, with or without the operating roll.

A further object of the invention is to 20 provide a peculiar construction of operating rod, to engage a ratchet wheel, such rod being integral and rigid, and dispensing with the ordinary pivoted pawl.

Other objects and advantages of the invention will be apparent during the course 25 of the following description.

In the accompanying drawings forming a part of this specification, and in which like numerals are employed to designate like 30 parts throughout the same,

Figure 1 is a side elevation of a rocking chair embodying my invention,

Figure 2 is a longitudinal section through the arm of the chair, the display belt being 35 in elevation,

Figure 3 is a side elevation of the chair, the door of the casing being open, and a portion of the operating drum broken away,

Figure 4 is a detailed section taken on 40 line 4-4 of Figure 3,

Figure 5 is a plan view of the arm of the chair,

Figure 6 is a vertical section, taken on line 6-6 of Figure 3,

45 Figure 7 is a detailed section taken on line 7-7 of Figure 3, and,

Figure 8 is a perspective view of the operating rod.

In the drawings, wherein for the purpose 50 of illustration is shown a preferred embodiment of my invention, the numeral 10 designates a rocking chair, as a whole, which may be of any well known or preferred construction. This chair embodies a back 11, seat 12, arms 13, legs 14, and rockers 15.

55 The arm 13 of the chair is included in a

side 13', having a casing 16 rigidly secured thereto. This casing embodies a top 17, serving as an arm rest. This top has an observation opening 18 formed therein. The 60 numeral 19 designates a door, hinged at 20 to the casing 16, and adapted to be held in the closed position by a latch 21, of any well known construction.

Arranged within the casing 16 is a rotatable drum 22, having a ratchet wheel 23 arranged upon the inner side thereof, and rigidly secured thereto. The drum and ratchet wheel have an opening extending centrally therethrough to receive a pivot 65 element or bolt 24, also passing through an opening in the side 13', as more clearly shown in Figure 6. At its outer end, the bolt 24 carries a nut 25, which may be removed to permit of the removal of the operating drum 22, when desired. A fibrous washer 26, formed of felt or the like, is 70 preferably interposed between the ratchet wheel 23 and the side 13'.

The operating drum 22 carries a display 80 element or belt 27, which may be formed of cloth, paper or the like, having advertising 28, Figure 5, printed upon the exterior thereof, as clearly shown. The upper portion of the display belt travels over guide 85 rolls 29, arranged within the observation opening 18, and pivoted upon pins 30 or the like, Figure 2. The ends of the display belt 27 are preferably detachably connected, by means of a detachable clasp 31, of any 90 well known or preferred construction. This permits of the removal of the display belt, with or without the drum 22, when it is desired to change the belt, to present different advertising matter.

95 The invention embodies a peculiarly shaped operating element, in the form of a rigid rod 32, having an intermediate transverse or horizontal portion 33, a lower upstanding or vertical portion 34, and an upper upstanding or vertical portion 35, the rod being bent at the points 36.

The numeral 37 designates a horizontal guide, rigidly attached to the side 13'. This guide has an elongated eye 38, receiving the 105 upstanding portion 35, preferably slidably contacting with the opposite sides of the eye, but spaced from the ends thereof. The transverse portion 33 is held within an eye 39, of a guide 40, which is vertically arranged, and rigidly attached to the side 13'. The eye 39 has its sides slidably contacting

with the portion 43, but the eye is elongated so that the portion 33 is spaced from the ends of the eye. The lower vertical portion 34 extends through a vertical opening 41, in the rocker 15, having a larger diameter than the portion 34, to permit of side play of said portion. The opening 41 leads into a chamber 42, receiving the portion 34, and a cap 43, preferably formed of rubber, secured on the end of the same. At its upper end, the portion 35 is bent at a right angle, forming a rigid dog 44, to engage with the ratchet wheel 23. A retractile coil spring 45 is attached to the portion 35, at 46, and to the side 13', at 47. A strip 48, preferably formed of felt, is secured to the side 13', and engages the portion 35.

The operation of the chair is as follows:

The chair is rocked back and forth by the user, and the cap 43, by contacting with the floor, effects a relative movement between the operating element 32, and the chair. The operating element is rigid throughout, and partakes of a relative longitudinal and horizontal movement, the same engaging beneath the teeth of the ratchet wheel, and effecting a step by step turning movement. The drum 22 is therefore turned, intermittently, which movement is imparted to the display belt 27, whereby the advertisements 28 are moved in succession within the opening 18, and hence may be readily observed by the occupant of the chair.

It is to be understood that the form of my invention herewith shown and described is to be taken as a preferred example of the same, and that various changes in the shape, size, and arrangement of parts may be resorted to without departing from the spirit 40 of my invention, or the scope of the subjoined claims.

Having thus described my invention, I claim:

1. In apparatus of the character described, the combination with a rocking chair, of an advertising device carried thereby, a ratchet wheel to advance the device, an operating element embodying an intermediate transverse portion and upper and lower upstanding portions, the upper end of the upper upstanding portion being bent laterally to provide a dog for engagement with the ratchet wheel, guides carried by the

chair and receiving the transverse portion and the upper upstanding portion and adapted to permit of longitudinal and transverse movements of the same, the lower end of the lower upstanding portion being adapted to contact with a floor, and a spring serving to draw the operating element laterally and downwardly.

2. In apparatus of the character described, the combination with a rocking chair, of an advertising device carried thereby, a ratchet wheel to advance the device, an operating element embodying a rigid rod bent to form an intermediate transverse portion and upper and lower upstanding portions, the upper end of the upper upstanding portion being bent laterally to provide a substantially horizontal dog to engage with the ratchet wheel, a horizontal guide carried by the chair and having an elongated eye to receive the upper upstanding portion, a vertical guide carried by the chair and having an elongated eye to receive the intermediate transverse portion, the lower end of the element contacting with the floor, and a spring to move the element downwardly and laterally.

3. The combination with a rocking chair, of a casing secured to one side thereof and having an inspection opening in its upper end, a door to close the open side of the casing, an operating drum detachably mounted within the casing, guide rollers held within said opening, a display belt traveling about the operating drum and rollers, and means to turn the drum including an element to contact with the floor.

4. The combination with a rocking chair, of a casing secured to one side thereof and having an inspection opening in its upper end, a door to close the open side of the casing, an operating device detachably mounted within the casing, a display belt coacting with said operating device and the inspection opening, and means to actuate the operating device including an element to contact with the floor.

In testimony whereof I hereunto affix my signature in the presence of two witnesses.

GENERAL E. BUTTON. [L. S.]
